UNITED STATES PATENT OFFICE.

HENRY G. PIFFARD, OF NEW YORK, N. Y.

DESIGN FOR A TANDEM-BICYCLE FRAME.

SPECIFICATION forming part of Design No. 26,739, dated March 9, 1897.

Application filed December 14, 1896. Serial No. 615,696. Term of patent 7 years.

To all whom it may concern:

Be it known that I, HENRY G. PIFFARD, a citizen of the United States, and a resident of New York, in the county of New York and State of New York, have invented a certain new and useful Design for Bicycle-Frames, of which the following is a specification.

The accompanying drawing, which forms a part of this specification, represents a tandem-bicycle frame of my design. In it the handle-posts A A' and the saddle-posts B B' are substantially parallel, as usual, and the posts B and A' are connected together in the usual manner, substantially as illustrated. So, also, the braces C D E, the connections F G, and the stay H are located in respect to the posts in substantially the same manner and relation as in the tandem frames now in use.

In the present design the departure from the common and well-known arrangement of parts occurs in the location of the stay I,

which, as illustrated, extends from the post A at a point adjacent to the junction of A and C horizontally across to the post B, which places the stay I considerably lower than the stay H. This location of the stay I may also be had in frames where one post is made to serve the purpose of the posts B and A', since it matters not what the special arrangement, form, and number of the posts and braces may be so long as the stay I sustains the relation to the handle-bar and saddle as herein shown and described.

I claim as my invention—
The design for a tandem-bicycle frame, substantially as shown and described.

Signed at New York, in the county of New York and State of New York, this 9th day of December, A. D. 1896.

HENRY G. PIFFARD.
